UNITED STATES PATENT OFFICE.

GEORGE EUGENE MITTINGER, OF YOUNGSTOWN, OHIO.

KNOCKDOWN METAL TANK.

Application filed December 20, 1921. Serial No. 523,619.

To all whom it may concern:

Be it known that I, GEORGE E. MITTINGER, a citizen of the United States, residing at Youngstown, in the county of Mahoning and State of Ohio, have invented certain new and useful Improvements in Knock-down Metal Tanks, of which the following is a specification, reference being had thereto in the accompanying drawing.

10 This invention relates to improvements in knock-down metal tanks, and is intended particularly for the storage of oil in what is known as "field" use.

15 The parts composing these tanks are transported to the nearest railway station and then transported sometimes for miles over rough country and in the field adjacent the well, or wells, to receive and store the oil therefrom.

20 So far as I am aware, heretofore these knock-down tanks have been composed of sheets of metal called staves, which have their adjacent edges lapped and riveted together with an intervening packing, which 25 requires thousands of rivet holes and rivets. These tanks are made of large capacity and are sometimes made several staves high. It has been found in practice extremely difficult and practically impossible to erect 30 tanks of this type in the field and have them leak tight and to remain leak tight. Furthermore, it is desirable at times to transport or move these knock-down tanks and in places where it is impractical to move 35 them in their erected form. Owing to the rivets it is expensive and almost impractical to tear the tank down and transport it to the desired place and re-erect it. In fact, it is practically as cheap to erect a new tank 40 in the desired position as it is to tear down a riveted tank and transport it to the desired point and re-erect it.

45 It is the primary object of my invention to provide a rivetless knock-down tank which is capable of quick erection and when erected will be liquid tight and remain liquid tight and is capable of being quickly and readily externally tightened at any point that a leak should occur and which 50 will not require expert work, such as is required in tank riveting.

Another object of my invention is to provide a rivetless knock-down tank which it is practical and economical to knock down 55 and transport and re-erect in the field.

Other objects of my present improvement will appear from the specification and drawings:

In the accompanying drawings:

Figure 1 is a perspective view showing a 60 metal liquid storage tank embodying my present improvement.

Fig. 2 is an enlarged side view of a tank embodying my improvement.

Fig. 3 is a vertical section of the metal 65 tank embodying my improvements, the same broken in two, intermediate the length of the staves.

Fig. 4 is an enlarged side elevation showing the method of joining and making liquid tight the adjacent vertical edges of the upper staves and the top edges of the lower staves.

Fig. 5 is a side elevation of the bottom edge of one of the lower staves and showing 75 two adjoining sections of the bottom and the method of making the joints of these parts liquid tight.

Fig. 6 is a reduced top plan view of the 80 sectional bottom for the tank.

Fig. 7 is a vertical sectional view through the bottom and the adjacent edge of one of the lower staves.

Fig. 8 is a detailed view showing the adjacent edges of two bottom sections, the 85 view taken at right angles to Fig. 7.

Fig. 9 is an enlarged detached view of the packing member used at the vertical edges of the upper staves and the horizontal top edges of the lower staves, and the manner 90 of making tight the abutting ends of the sectional packing members.

Fig. 10 is a perspective of a straight section of the packing member.

Fig. 11 is a detached perspective view of 95 the packing member used at the junction of the edges of the sectional bottom and the adjacent lower edge of the vertical stave.

Referring now to the drawings, in which similar reference characters denote the same parts, my improved knock-down tank consists of a plurality of staves 1, and where the tank is made more than one stave high, a plurality of vertical staves 2. In Fig. 1, I have shown the tank round in form, but 105 I desire it to be understood that the tank may be of any cross-sectional form without affecting my present improvement.

In carrying out my present improvement, I provide the side margins or edges of the 110

staves with lateral flanges *a* and their top and bottom edges with laterally extending flanges *b*. These side and bottom flanges each is provided with a curved portion 4 and an inner straight portion 5, as clearly shown in Figs. 3 and 7.

The bottom is composed of a plurality of sections as 6, 7, 8 and 9. This bottom is made of a size larger than the circumference of the tank equal to the length of the straight portion 5 of the flange at the bottom edges or margins of the vertical staves 2, as shown at 9, and the peripheries of the sections are provided with curved portions 10, which register or correspond to the curved portions 4 of the flange of the staves 2. It will be observed by reference to Fig. 7 that the portion 4 of the stave is curved upwardly, while the portion 10 of the sections of the bottom is curved downwardly, whereby a round, or approximately round space is formed between the two curved portions to receive a suitable compressible packing 11, which is correspondingly shaped. This packing member 11 also has a laterally extending flange 12, which extends between the portions 5 and 9 of the bottom stave, as in Fig. 7, and extends between the corresponding straight portions 5 of the side edge flanges of both the upper and lower staves. The straight edges of the sections of the bottoms are provided with depending flanges which have curved portions 13 and straight portions 14, which are the same shape as the straight and curved portions 4 and 5 of the staves, except that the ends of these bottom flanges extend upward and merge into the curved portions 10 at the peripheries of the bottom sections, as shown at 15, Fig. 7.

The packing member, shown in Fig. 11, comprises the round portion 11 and the lateral flange 12, and also a downwardly and inwardly curved round portion 16, which merges into the round portion 11 to correspond with the shape 15 of the flanges in Fig. 7, and then an inwardly extending straight round portion 17 fitting between the curved flanges 13 at the straight edges 50 of the bottom sections 6, 7, 8 and 9.

In Fig. 9, I show the shape of the packing member at the adjacent vertical edges of the upper staves and the top horizontal edges of the lower staves, and it consists essentially of a T, as clearly shown in that figure, the round portions 11 of the T merging into each other and the lateral flanges of the round portions of the T also merging into each other, as shown in Fig. 9.

In practice these packings are made in sections and for the purpose of making a liquid tight joint between the adjacent edges of the sections of the packing, one adjacent end is provided with an opening 18 and the adjacent end 19 of the other section ex-

tends into this opening. The end 19 may or may not be reduced since the wall of the opening 18 will be thin so that when the packing is compressed, it will make a tight fit in between the curved portions of the flanges and also a liquid tight joint between the adjacent ends of the several sections of the packing.

The staves and the sections of the bottom are clamped in assembled positions and the packing compressed between the flanges to make a liquid tight joint by means of a plurality of clamping members *c*. These clamping members comprise two parts, one a hooked shaped member 20, which is provided with a screw-threaded stem 21, a block 22 through which the screw-threaded stem 21 passes, the block having its inner side curved as at 23, and a nut 24 on the screw-threaded stem 21. These two members 20 and 22, of several separate clamps, are placed in position to embrace the outer surfaces of the adjacent curved portions of the staves, and the curved portions of the flanges of the staves and the bottom, and of the curved portions of the flanges of the straight edges of the sections of the tank bottom.

There will be a sufficient number of clamps *c* for each pair of flanges to cause a proper compression of the packing between the flanges to make a liquid tight joint, the number of clamps used will depend somewhat upon the thickness and rigidity of the flanges. That is to say, it will require a greater number of flanges for relatively thin material than it would be required for stout heavy material, and a more or less number of clamps than that shown in the drawing for each seam could be used according to the necessity of the structure.

It will also be readily understood that by means of these adjustable clamps *c*, the joints can be tightened from time to time if it should be necessary and if there should be a leak at any particular point, an additional clamping member can be added exteriorly at that point for the purpose of causing additional compression of the packing at that point.

By means of a knock-down metal tank of the construction here shown, the staves or sheets composing the tank will be shipped in a knock-down nested form, together with the clamping members, and the tank readily and quickly erected at the desired point without the necessity of especially skilled mechanics, such as would be required for water-tight applying thousands of rivets as in the old riveted tank. Furthermore, the tank can be knocked down and transported and re-erected without the necessity of especially skilled mechanics. The staves are strengthened by the marginal flanges,

so that they will be held in their original proper shape even when subjected to rough handling, such as they will get in transporting over rough country.

5 Where the tank is round in cross-section the packing member 11, shown in Fig. 11, will be curved to correspond to the curve of the bottom of the tank, but if the tank has straight sides, this member 11 will be 10 straight, as shown in Fig. 11.

Attention is directed to the fact that the flanges of the upper tier of staves, which form the joint is located intermediate the side edges of the staves forming the tier 15 below the tank. Attention is also directed to the fact that the flanges on the straight edges of the sections which form the bottom are so located that they come between the straight edges of the lower tier of staves.

20 By reason of these two arrangements the seams of the staves forming the relatively upper and lower tiers of the tank add greatly to the strength and rigidity of the structure when completed.

25 I desire it to be understood that with this construction of knock-down metal tank, the tank may be composed of any practical number of tiers, and the tank may be provided with any suitable or well-known 30 form of cover, either a duplicate of the sectional bottom, or any other desired form of cover.

I wish it also to be understood that the flanges or the edges of the staves and sections of the bottom will afford the necessary stability and shape holding characteristics to hold their shape in transportation over rough ground, and in handling in erection, etc.

40 I do not limit myself to the exact construction herein shown and described, for this may be varied without departing from the spirit and scope of the invention as expressed in the appended claims.

45 Having thus described my invention, what I claim and desire to secure by Letters Patent is:

1. A knock-down tank comprising two horizontal rolls of vertical staves, the said 50 staves arranged in staggering relation, said staves having outwardly extending vertical flanges on their edges and horizontal flanges

on their bottoms, packings between the flanges, said packing being T-shaped at the junction of the vertical and horizontal 55 flanges, and clamps for the said flanges.

2. A knock-down metal tank comprising a plurality of vertical staves and a bottom, said staves having outwardly extending flanges on their vertical edges and outward- 60 ly extending flanges on their bottoms, said bottom composed of a plurality of transversely arranged members having outwardly extending flanges on their sides and peripheries, the ends of the side flanges turned 65 outward and merging into the peripheral flange, and packing between the flanges corresponding to the said shape, and clamps clamping the said flanges.

3. A knock-down metal tank comprising 70 a plurality of vertical staves having at their vertical and bottom edges laterally and outwardly extending flanges having bent portions to form oppositely extending grooves, a bottom composed of a plurality of transverse sections having their transverse edges provided with downwardly extending flanges bent to form oppositely extending grooves at their adjacent faces, and the outer edges of the sections having outwardly ex- 80 tends bent portions under the flanges at the bottoms of the vertical staves, the outer ends of the transverse flanges of the bottom sections extending upwardly and merging 85 into the horizontal bent flanges on the outer edges of the bottom sections and a plurality of clamping members embracing the said flanges, for the purpose described.

4. A knock-down metal tank comprising 90 a plurality of vertical staves having flanges with packing between them, clamping members comprising two parts, one part engaging 95 one of said flanges and curved inward, a second member engaging the opposite flange, said second member having an opening through which said curved portion passes, the curved portion extending beyond the member and screw threaded, and a nut on the screw-threaded end, whereby the clamping action is in a direct line with 100 the said flanges.

In testimony whereof I hereunto affix my signature.

GEORGE EUGENE MITTINGER.
